UNITED STATES PATENT OFFICE

HUGH R. MACMICHAEL, OF EL PASO, TEXAS, ASSIGNOR TO AMERICAN SMELTING AND REFINING COMPANY, OF NEW YORK, N. Y., A CORPORATION OF NEW JERSEY

CHARGING MACHINE FOR SCOTCH HEARTHS

Application filed January 18, 1928. Serial No. 247,530.

This invention relates to smelting apparatus, and more particularly to mechanism for feeding a hearth type furnace.

The feeding mechanism in accordance with 5 this invention comprises a suitable supply hopper, feeding onto a traveling conveyor which delivers the charge to a feeding chute.

The chute is formed of a plurality of sections, terminating over the hearth and may 10 be moved longitudinally thereof for evenly distributing the charge. The sections are particularly adapted to distribute the charge to the furnace at substantially right angles to the line of travel of the chute whereby substantially 15 the entire hearth area may be covered.

The invention also consists in certain new and original features of construction and combinations of parts hereinafter set forth 20 and claimed.

Although the novel features which are believed to be characteristic of this invention will be particularly pointed out in the claims appended hereto, the invention itself, as to 25 its objects and advantages, the mode of its operation and the manner of its organization may be better understood by referring to the following description taken in connection with the accompanying drawings forming a 30 part thereof, in which

Fig. 1 shows an end view of the carriage and feeding mechanism and a section through the furnace;

Fig. 2 is a section view showing details of 35 the feeding chute;

Fig. 3 is a side elevation of the carriage equipped with the feeding mechanism, looking toward the back of the furnace;

Fig. 4 is a sectional view showing the construction of the conveyor;

Fig. 5 is a plan view of the conveyor and chute;

Fig. 6 is a detail view showing the gates for controlling the flow of the charge to the conveyor; and

Fig. 7 is a section taken on the line 7—7 of Fig. 6.

Like reference characters denote like parts in the several figures of the drawings.

50 In the following description and in the

claims parts will be identified by specific names for convenience, but they are intended to be as generic in their application to similar parts as the art will permit.

Referring now to the drawings, and, more 55 particularly to Fig. 1, so much of a hearth as is necessary to an understanding of the invention will be described. The hearth comprises the usual trough 1, relatively shallow and narrow, but comparatively long. At the 60 front end of the trough is a forwardly and slightly downwardly sloping apron 2. At the back of the trough is the furnace back which has a hollow space 3, in which cooling 65 water may be circulated. Below the cooling space are a series of tuyères 4, extending the length of the furnace for supplying the necessary draft, as is well understood. Above the back is a canopy or hood 5 for catching the fumes and gases given off by the furnace. 70 The particular construction of the hearth, however, forms no part of the present invention and will not be described in detail.

Extending along in front of the furnace are two overhead track rails 6 supporting a 75 traveling carriage 12 supported by two axles 7 and 8, each axle having two wheels 9. The carriage is made up of suitable structural members and may support rabbelling and shovelling mechanism (not shown) in addition to the feeding mechanism which is described more in detail hereinafter.

For driving the carriage 12 an electric motor 10 is provided which is connected to one of the axles 8 through a gear train comprising cog wheels 11 and 14, and a worm drive reduction unit 15. It will be understood that the wheels 9 are rigidly secured to the axle 8, and that the gear train may be varied as desired.

The motor 10 is of the reversible type and may have provision for running at an increased speed when reversed. The carriage is adapted to travel in front of the hearth and is provided with a reversing switch (not shown) for controlling the motor 10. At the end of its operating trip the reversing switch lever may hit a suitable stop (not shown) which causes the motor 10 to reverse, thereby causing the carriage to return to its start. 100

ing position at increased speed. At the starting position the switch lever may hit another stop (not shown) which causes the motor to reverse again, thereby causing the carriage to travel on its operating trip at the slower operating speed.

The carriage frame supports a suitable hopper 25 into which the charge, comprising pre-mixed quantities of ore, fume and fuel 10 in a finely divided condition, may be delivered in any desired way. Hopper 25 tapers downwardly as shown in Figs. 1 and 3 and is provided with a side discharge opening 26, the size of which may be controlled by 15 suitable gates 27.

Gates 27 may extend across the face of the hopper and serve to independently regulate the amount of material which is discharged from the various portions thereof. The 20 gates may be provided with a curved bottom portion 28 and with an upstanding top portion 29 serving as a handle therefor. They may be slidably adjusted and secured by bolts 30 passing through slots 31 extending 25 longitudinally thereof and secured in hopper 25 adjacent the opening 26 therein.

A traveling belt 35 is supported by carriage 12 adjacent the opening 26 of hopper 25. Said belt may be supported on a plurality of rollers 36 and driven by any suitable means from motor 16 as by reducing gear 37 and chain drive 38. The tension of belt 35 may be regulated by adjusting the position of the axle of one of the end rollers 35 40 (Fig. 4) which may be carried in cross head 41 slidably mounted in groove 42. The position of cross head 41 may be adjusted by bolts 43. Intermediate rollers 36 serve to support the belt at the point where the charge 40 is applied and prevent the weight of the charge from materially distorting the line of travel thereof.

Belt 35 after receiving a charge from hopper 25 discharges the same into chute 44 45 through the medium of a discharge hopper 45. Chute 44 (Figs. 1 and 2) comprises a plurality of feeders 46 superimposed in vertical relationship and extending over various portions of hearth. Ends 47 of feeders 50 46 may be of diagonal or slightly curved formation for suitably spreading the charge transversely of the hearth. The innermost portion of the end 47 of upper feeder 46 is substantially in the same line as the outermost portion of the next adjacent or second feeder and this same relationship is carried out through the entire assembly. By this arrangement the charge is distributed throughout the entire width of the hearth and the 55 triangular portion at the end of the hearth which the feeder has heretofore been unable to cover is reduced to a small percentage of that present with a chute having the feeders arranged in a single layer with a diagonal 60 end.

Chute 44 may be mounted by flexible members 48 and vibrated by suitable mechanism as by eccentric 50 secured by means of link 51 to an arm 52 attached to said chute. Said eccentric may be rotated directly from motor 16 as by belt drive 53 (Fig. 5) and cooperating driving pulleys 54 and 55. The amount of material discharged from hopper 25 into the various feeders 46 by chute 44 may be controlled by selectively regulating gates 27 75 whereby the distribution of the material across belt 35 is varied. The upper ends of feeders 46 are suitably positioned for receiving material through discharge hopper 45 in substantial alignment with openings 26 in 80 hopper 25. Consequently the material discharged from a specified portion of hopper 25, as determined by slides 27, is carried by belt 35 to the selected feeder.

The slope of the chute 44 may not be sufficient to cause the charge to flow down unless the chute is shaken. Consequently the driving mechanism has been adapted to cause the chute to shake or vibrate in the manner above described, the loose spring mountings 48 allowing this action. The slope of chute 44 should be such that the vibrations imparted to said chute are able to cause the charge to travel the length thereof and to be spread across the hearth from diagonal ends 47. 95 The chute may be mounted in a horizontal position and the charge caused to travel therein by means of a suitable reciprocating motion if desired. Obviously, if the slope of the chute is made sufficiently great the vibrating mechanism can be dispensed with and the charge fed entirely by gravity.

As the carriage travels on its operating trip, the charge will be fed down the feeders 105 46, and its distribution on the hearth will be controlled by the opening of the gates 27. Suitable means may be provided for stopping the operation of belt 35 during the return trip of the carriage in order to prevent the apparatus from feeding at that time.

The mounting of the various feeders in vertical relationship with their ends extending transversely of the hearth by graduated distances permits the charge to be evenly 110 spread across the entire hearth, and enables the feeder to work substantially to the end of the hearth. The traveling belt and the various gates arranged thereacross permit the rate of feed to the various feeders to be 115 varied as desired.

The arrangement is such that very accurate control of spreading may be obtained, and by pre-mixing the fuel, ore and fume, a very efficient smelting action may be obtained. 120 The poking operation followed by the leveling or shoveling operation above described may precede the feeding operation, and the poking and shoveling operations as above described, may be performed by apparatus (not 125 130

shown) mounted on the carriage, or may be performed by hand.

Thus an automatic feeding mechanism has been provided for a hearth type furnace which is effective and efficient in operation. The distribution of charge on the hearth can be readily controlled to meet different operating conditions imposed by various causes such as changes in the ore and in the condition of the fire. The relative distribution across the hearth may be controlled by operation of the gates to allow different amounts of charge to be fed down the several feeders. The relative distribution along the length of the hearth may be controlled by changing the position of the gates along the path of travel of the carriage. The arrangement is simple and rugged in construction, insuring long life and small expense of upkeep. The feeding mechanism requires no great skill to operate and aids materially in maintaining a uniform and effective fire throughout the hearth, resulting in maximum metal recovery from the ore.

While certain novel features of the invention have been shown and described and are pointed out in the annexed claims, it will be understood that various omissions, substitutions and changes in the forms and details of the device illustrated and in its operation may be made by those skilled in the art without departing from the spirit of the invention. Obviously coke and ore may be separately applied to the hearth through different feeding devices if desired.

What is claimed is:

1. In combination with a hearth type furnace, a feeding mechanism therefor comprising a framework, means for moving said framework longitudinally of said hearth, a hopper carried by said framework for receiving the charge, a traveling belt for receiving material from said hopper, and a chute extending over said hearth adapted to receive material from said belt, said chute comprising a plurality of feeders arranged in vertical alignment.

2. In combination with a hearth type furnace, a feeding mechanism therefor comprising a framework, means for moving said framework longitudinally of said hearth, a hopper carried by said framework for receiving the charge, a traveling belt for receiving material from said hopper, and a chute extending over said hearth adapted to receive material from said belt, said chute comprising a plurality of feeders arranged in vertical alignment, said feeders having their ends of approximately diagonal formation and progressively displaced across said hearth.

3. In combination with a hearth type metallurgical furnace, a feeding mechanism therefor comprising a hopper having a discharge opening and a feeding chute comprising a plurality of feeders arranged in different horizontal planes, a plurality of gates for regulating the size of said discharge opening, each of said gates being adapted to control the material fed to a selected feeder.

4. In combination with a hearth type metallurgical furnace, a feeding mechanism therefor comprising a supply hopper, a traveling belt adapted to receive a charge therefrom, a plurality of feeders, means for discharging material from said belt onto each of said feeders simultaneously, and means associated with said hopper for adjustably controlling the material applied to each of said feeders.

5. In combination with a hearth type furnace, a feeding mechanism therefor, comprising a plurality of chutes having diagonal end portions, said end portions being spaced vertically and horizontally, and means for feeding material to be discharged to said chute.

In testimony whereof I have hereunto set my hand.

HUGH R. MACMICHAEL.
